UNITED STATES PATENT OFFICE.

EUGEN HABERFELD, OF BERLIN-HALENSEE, GERMANY, ASSIGNOR TO LATHAM
LITHO & PRINTING CO., OF NEW YORK, N. Y., A CORPORATION OF NEW YORK.

DEVICE FOR PRODUCING AN OPTICAL ILLUSION.

Application filed March 18, 1926. Serial No. 95,522.

My invention consists in a device composed of a stationary surface and a movable surface disposed back of said stationary surface and carrying the picture of some article, or the like, arranged in such a position on said movable surface that upon the latter being set into motion, the picture thereon will appear in certain time intervals in an opening or window provided in the stationary surface. On the front of this stationary surface there may be printed, for instance, a cigarette box, and at some distance below the same another box or container, the opening above referred to, consisting in this case of a slot disposed between the cigarette box and the said container. On the movable surface disposed back of the stationary surface there is painted or otherwise shown a cigarette, the picture thereof being so arranged that upon the said movable surface being set into motion, the picture of the cigarette will in certain time intervals appear in said opening, the whole arrangement giving the illusion as if a cigarette were continually 25 dropped from the cigarette box into the container below. The movable surface which is painted or made of the same color, preferably a dark color, as the stationary surface, may be made as a rotatable circular 30 disk and may carry several pictures of a cigarette suitably spaced, of course, apart. The movable surface and the means for moving the same are concealed by a casing, the front wall of which casing is preferably 35 formed by the stationary surface.

While a cigarette has been mentioned, it will be obvious, that the device will readily lend itself to any kind of article, or even to produce other optical illusions. For instance, there may be pictured on the stationary surface a coffee-pot in a tilted position as if to pour out coffee, and on the movable surface there would then be painted a brown streak, which if more or less continually appearing through the opening in the stationary surface, would create the illusion, as if actually coffee was being poured from the coffee pot. In that case, of course, a cup would be shown below the coffee-pot, the opening being disposed between the cup and the pot. Or in returning again to the picture of a cigarette, there may be shown on the stationary surface a hand holding a burning cigarette, and an opening is provided above the end of the cigarette. On the

movable surface back of the stationary surface there are pictured small curls of smoke, so that upon the movable surface being set into motion, the impression will be created as if curls of smoke rise from the burning 60 end of the cigarette.

Thus, it will be seen that my invention is capable of almost innumerable modifications, variations and applications, and therefore I do not limit myself to the constructions shown in the accompanying drawing 65 and hereafter described in detail.

In the drawing, Fig. 1 shows one form of my invention in front elevation, Fig. 2 shows the movable surface and the means for moving the same, Fig. 3 shows a different movable surface and means for moving the same.

In Fig. 1 is shown a stationary surface 1 which is provided with an opening or window shown at 2. On this stationary surface 75 which for obvious reasons is made of a dark color, preferably black or dark blue, may be painted, as in the example shown, a cigarette box as shown at 3, and below the same is painted a container shown at 4, the opening 80 2 being arranged between the cigarette box 3 and the container 4.

Back of the stationary surface 1 entirely concealed thereby is the movable surface which may be of any desired contour and 85 which may be flat or curved. In the example shown, this movable surface is made as a circular disk 5 (Fig. 2), and on this circular disk which is of the same dark color as the stationary surface there are shown at 6 90 and 7 two pictures of a cigarette so arranged that on the rotation of the said disk close behind the stationary surface, the pictured cigarettes will in certain time intervals appear in the opening or window 2 and disappear again. In the person standing in front of the stationary surface the illusion of a cigarette continually dropping from the cigarette box 3 into the container 4 is created. Instead of two cigarettes being pictured on the disk 5, of course three or four cigarettes may be pictured, or only one as 95 may be desired.

The disk 5 is rotatably mounted on a spindle 8 which is journaled in a bearing 9 and 100 may be driven from any desired source of power such as a small electric motor shown in broken lines in Fig. 2.

According to the modification shown in Fig. 3, the cigarette may be pictured on an 110

endless strip 10 made of strong paper, or any other suitable material. In that case, the strip 10 is passed over two rollers 11, 12, one of which may be rotated by means of a 5 pulley from any suitable source of power (not shown).

Other modifications, such as a rotatable 10 drum, carrying pictures of articles, will easily suggest themselves as being adaptable 15 for creating the desired illusion.

I claim:

1. The combination of a stationary surface having an opening, a movable surface disposed back of said stationary surface and 15 carrying the picture of some article, or the like arranged to move across said opening at certain time intervals, and means for setting 20 said movable surface into motion said movable surface and said stationary surface being similarly colored.

2. The combination of a stationary surface having an opening, a movable surface disposed back of said stationary surface and carrying the picture of some article, or the 25 like, arranged to appear in certain time intervals in said opening, and a means for moving said movable surface at a uniform rate of speed, said movable surface and said stationary surface being similarly colored.

3. The combination of a stationary surface having an opening, a movable surface disposed back of said stationary surface and carrying one or more pictures of some article, or the like, arranged to appear in certain time intervals in said opening, means 30 for moving said movable surface at a uniform rate of speed, and a casing enclosing said movable surface and said means and being closed in front by said stationary surface, said movable surface and said stationary 35 surface being similarly colored.

4. The combination of a stationary surface having an opening, a circular rotatable surface disposed back of said stationary surface, and carrying one or more pictures 40 of some article, or the like, arranged to appear in certain time intervals in said opening, and a means for rotating said circular surface at a uniform rate of speed, said movable surface and said stationary surface being similarly colored.

5. The combination as specified in claim 4 comprising also a casing concealing said rotatable surface and said rotating means, the front wall of said casing being formed 45 by said stationary surface.

In testimony whereof I affix my signature.

EUGEN HABERFELD.
